UNITED STATES PATENT OFFICE.

JOHN HOFERLE, OF CHICAGO, ILLINOIS, ASSIGNOR OF ONE-FOURTH TO HENRY A. HOFERLE, ONE-FOURTH TO ANDREW AUER, AND ONE-FOURTH TO LOUIS AUER, ALL OF CHICAGO, ILLINOIS.

DOOR CHECK AND CLOSER.

1,133,725.

Specification of Letters Patent. Patented Mar. 30, 1915.

Application filed March 30, 1914. Serial No. 828,182.

To all whom it may concern:

Be it known that I, JOHN HOFERLE, a citizen of the United States, residing at Chicago, in the county of Cook and State of Illinois, have invented certain new and useful Improvements in Door Checks and Closers, of which the following is a specification.

My invention relates to an improvement in the class of door checks wherein the door is closed by means of a suitable contraction spring and is checked or retarded in its closing motion by means of a cushion of air or other fluid in order to retard the final movement of the same and prevent the slamming thereof.

A further object of my invention is to construct a door check and closer in as simple a manner as possible to avoid the same getting out of order, and to reduce the parts to a minimum number in order to decrease the cost of manufacture but without detracting from its efficiency.

The above and still other objects I accomplish by the means and in the manner hereinafter fully described and as more particularly pointed out in the claims, reference being had to the accompanying drawings forming a part of this specification, wherein:

Figure 1 is a horizontal plan view of my improved door check and closer applied to a door and frame, showing the door closed; Fig. 2 is a view similar to Fig. 1, showing the door open at substantially a right angle to the door frame; Fig. 3 is a vertical end elevation of the same showing the door in the position shown in Fig. 2; and, Fig. 4 is an enlarged sectional view taken on line 4-4 of Fig. 3, showing the adjustable connection between the two arms or toggle.

Referring to the drawings, A represents a suitable door that is supported by hinges on one of its vertical edges that are secured to the frame B, surrounding the door opening in the wall of the building. The door check and closer itself comprises a cylindrical or tubular member 6 in which a suitable piston 7 is adapted to operate and these two parts are constructed and arranged in substantially the same manner as described in a pending application for United States Letters Patent filed December 26, 1912, Serial No. 738,558, and need not therefore be de-

scribed in detail herein. Suffice it to say, 55 however, that the piston-rod 7 in this instance is hollow and a coiled contraction spring α is inclosed thereby, one end of said spring being connected to the closure cap at the outer end of the piston-rod while the opposite end of said spring is similarly connected to the closure cap at the outer end of the cylindrical or tubular member 6, in the same manner as illustrated in the drawings of the above referred to application. 60 65

The outer end of the piston rod 7 is provided with a pivotal lug that is adapted to be inserted between the parallel arms of a bifurcated pivot bracket 8 secured to the lintel or upper horizontal member of the 70 door-frame. The outer end of the cylinder 6 is supported upon the hinge of a suitable toggle one of the members of which comprises a horizontally disposed substantially L-shaped arm 10 that has its upper end 75 reduced to form a pintle 11 that is screw-threaded and passes up through an opening in a lug 9 projecting longitudinally from the cap on the outer end of the cylinder 6. Said L-shaped arm 10 has its inner end 80 bifurcated and pivotally mounted on a bracket 12 secured in any suitable manner to the upper edge of the door and which is so positioned that said arm under normal conditions is in a plane at substantially 85 right angles to the plane of the door when closed. The other member of this toggle comprises an extensible or adjustable link, the inner member 13 of which is pivotally secured to the door frame above the door by 90 means of a bracket 14 and having its shank screw-threaded to fit into the screw-threaded bore of the other member 13^a thereof. Member 13^a is preferably bent or deflected laterally at its outer end and is adapted to 95 be adjustably and pivotally mounted in a slotted lateral boss 10^a that is formed on one side of the shorter vertical portion of the L-shaped arm 10 before mentioned, which pivot is below and substantially in axial 100 alinement with the pintle 11 for the cylinder.

It will be observed from the above that the pivotal point of the outer end of the cylinder being in alinement with the pivot 105 or hinge of the toggle and the pivotal end of the piston being at an acute angle to the axis of said arm 10 the tendency of the con-

traction spring α is to close the door. When, however, the door is opened to such an extent that the "pull" of the spring is on an approximate dead-center with the axis of said arm 10 the energy of said spring will not be transmitted to said arm and the door will remain in an opened position. This contingency will not occur until the door has been opened to an angle of more than a right angle (90°) to the plane of the door frame.

Having thus described my invention what I claim as new and desire to secure by Letters Patent, is:—

1. A door check and closer comprising a cylinder and plunger therefor, means carried thereby for effecting the closure of the door, and a toggle consisting of a straight link and a substantially L-shaped link the shorter arm of which is vertically disposed, an off-set member projecting laterally from the shorter arm of said L-shaped link to which the opposite link is pivotally connected and to the end of said shorter arm said cylinder is pivotally connected.

2. A door check and closer comprising a cylinder and plunger therefor, means carried thereby for effecting the closure of the door, and a toggle consisting of a straight

link and a substantially L-shaped link the shorter arm of which is vertically disposed, an off-set member projecting laterally from the shorter arm of said L-shaped link and provided with a slot and having several openings transverse to said slot in one of which the adjacent end of the opposite link is pivoted, and to the upper end of said shorter arm said cylinder is pivotally connected.

3. A door closer and check comprising a cylinder and a piston therefor, means for retracting said piston within said cylinder, a bracket pivoted to the outer end of said piston, a toggle consisting of two links adjustably pivoted together and pivotally connected at their hinged ends to the base of said cylinder, one of said links pivotally secured to the door opposite the base of the cylinder and the other of said links pivotally secured to the door casing adjacent the place of attachment of the first-mentioned link when the door is closed.

In testimony whereof I affix my signature in the presence of two witnesses.

JOHN HOFERLE
